Primary Examiner — Michelle E. Wilson*Assistant Examiner* — Rochel L Rimelspach-Zare(74) *Attorney, Agent, or Firm* — Birchwood IP(57) **CLAIM**

The ornamental design for a toy, as shown and described.

DESCRIPTION

FIG. 1 is a front, right and bottom perspective view of a toy, showing my new design;

FIG. 2 is a rear, left and top perspective view thereof;

FIG. 3 is an expanded view of FIG. 1;

FIG. 4 is a front view thereof;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.

The broken lines shown in the drawings illustrate portions of the toy that form no part of the claimed design.
